UNITED STATES PATENT OFFICE.

MABEL AARON, OF STOCKTON, CALIFORNIA.

ATTACHMENT FOR TYPE-WRITERS.

1,081,185.

Specification of Letters Patent.

Patented Dec. 9, 1913.

Application filed August 17, 1912. Serial No. 715,625.

To all whom it may concern:

Be it known that I, MABEL AARON, a citizen of the United States, residing at Stockton, in the county of San Joaquin, State of California, have invented certain new and useful Improvements in Attachments for Type-Writers; and I do declare the following to be a full, clear, and exact description of the same, such as will enable others skilled in the art to which it appertains to make and use the same, reference being had to the accompanying drawings, and to the characters of reference marked thereon, which form a part of this application.

15 This invention relates to improvements in attachment for typewriters the object of the invention being to produce an attachment adapted to receive and hold the stenographic notes or other papers from which transcription is being made by the typewriter, such holder being designed to fit any typewriter and being adjustable vertically and laterally to enable it to conform to different sizes of papers or note books.

20 25 A further object of the invention is to produce a simple and inexpensive device and yet one which will be exceedingly effective for the purposes for which it is designed.

These objects, I accomplish by means of 30 such structure and relative arrangement of parts as will fully appear by a perusal of the following specification and claim.

In the drawings similar characters of reference indicate corresponding parts in the 35 several views.

Figure 1 is a front elevation of the complete device, partly broken out. Fig. 2 is a side elevation partly in section taken on a line X—X of Fig. 1.

40 Referring now more particularly to the characters of reference on the drawings, the numeral 1 designates the back plate of the typewriter and my improved attachment comprising three bars 2 each provided with 45 a pair of spaced vertical flanges 3 adapted to receive the plates 1 between them and to secure such plates 1 in position by means of wing nuts 4 projecting through one of the flanges 3 and adapted to impinge it tightly

50 against the other flange. Each of the plates 2 is provided with suitable rubber or similar supporting feet 5. On each of the members 2 is a vertical rod 6. Slidable over the two outer rods 6 is a lower frame comprising a 55 central member 7 and two outer members 8

such member 7 being telescoped into the outer members 8 whereby the length of the frame may be adjusted laterally. Said frame 7—8 is provided with a projecting supporting shelf 9 which is also telescopically made to permit of the lateral adjustment. The central member 6 is threaded to receive a thumb screw 10 which supports the member 7 and incidentally the entire frame 7—8 and by turning the screw 10 such frame 65 7—8 may be adjusted vertically for the purpose of fixing the device to hold different size books or papers. Spaced from the frame 7—8 is another similar frame 11—12 constructed similarly to the frame 7—8 and the same is also held and adjusted in position by means of a thumb screw 13 mounted on the threaded rod 6. Hinged to the upper end of the frame 11—12 is a spring pressed bar 14 having an operating handle 15 for 70 raising and lowering, which bar is adapted to receive the paper or book underneath it and hold the same in fixed position on the frame during its use.

The numeral 16 designates the springs 80 which press against the bar 14 to hold it in position. Secured to one of the members 6 near its upper end is an elastic band 17 having a plurality of holes 18 in one end adapted to engage a hook 19 on a collar 20 mounted on the opposite rod 6 which elastic band can be used for holding extra length papers or books in upright position on the frame. The band 17 and the collar 20 are of course 85 capable of moving vertically on their respective rods 6 when the balance of the frames are adjusted thereon.

In practice the book or paper to be copied from is mounted on the platform 9 and engaged under the member 14 or the band 17 95 and as can be readily seen as the device is attached to the rear of the typewriter it brings the work directly before the operator rendering it to be easily seen and transcribed.

From the foregoing description it will be readily seen that I have produced such a device as substantially fulfills the object of the invention as set forth herein.

While this specification sets forth in detail the present and preferred construction of the device, still in practice such deviations from such detail may be resorted to as do not form a departure from the spirit of the invention.

Having thus described my invention what I claim as new and useful and desire to secure by Letters Patent is:

A device of the character described comprising supporting members, three upwardly projecting rods on said supporting members, the central one of said rods being threaded, a central frame member movable vertically over said threaded rod, a thumb screw mounted on said threaded rod and adapted to engage said central frame, a frame mov-

able vertically on each outer rod, each of said last named frames being telescoped over said central frame in sliding relation therewith, as described.

15

In testimony whereof I affix my signature in presence of two witnesses.

MABEL AARON.
